UNITED STATES PATENT OFFICE.

GUSTAVE H. PRIGAN, OF BURNS, MONTANA, ASSIGNOR OF ONE-THIRD TO EDWARD H. FULLER AND ONE-THIRD TO ARTHUR WHITE, BOTH OF BURNS, MONTANA.

SECURING DEVICE FOR THE CONNECTING STRIPS OF AUTOMOBILES.

1,425,691.

Specification of Letters Patent. Patented Aug. 15, 1922.

Application filed December 27, 1920. Serial No. 433,346.

To all whom it may concern:

Be it known that I, GUSTAVE H. PRIGAN, a citizen of the United States, residing at Burns, in the county of Richland and State 5 of Montana, have invented certain new and useful Improvements in Securing Devices for the Connecting Strips of Automobiles, of which the following is a specification, reference being had to the accompanying 10 drawings.

This invention relates to securing devices for the connecting or padding strips of automobile bows.

As is well known to those familiar with 15 the art, the usual automobile top of the foldable type is supported by a plurality of inverted U-shaped members usually designated as bows, and these U-shaped members are connected at the bends, connecting the arms 20 and the bows of the U by padding strips extending longitudinally of the bight portion and serving the purpose of properly spacing the bows and of supporting the bend of the fabric cover properly. These strips 25 are generally secured to the bows by means of tacks or nails driven through the strips and into the bows; and due to the strain to which the bows are subjected both when the top is extended and when the top is in the 30 folded position, the heads of these nails often work through the cloth of the strip permitting the strip to work loose and sag and cause the top to present an unsightly appearance.

An important object of the invention is 35 to provide a simple and efficient attaching member for these strips whereby to prevent their working loose from the bows and to this end the invention consists broadly in a 40 plate bent to conform to the curvature of the bow at the point of application of the strip thereto, and providing upon its inner surface piercing points adapted to extend through the strip and into the bow, the plate 45 being provided with suitable means whereby it may be attached to the bow.

A further object of the invention is to 50 provide a device of this character which may be readily formed from a single strip of sheet metal, thereby providing a device which is economical and simple in its manufacture.

Other objects and advantages of the in-

vention will become apparent throughout the course of the following description: 55

In the accompanying drawings, wherein for the purpose of illustration is shown a preferred embodiment of my invention, and wherein like reference characters designate like parts throughout: 60

Figure 1 is a fragmentary side elevation, partly in section, of the automobile bow and connecting strip having my fastening device applied thereto;

Figure 2 is a plan view of a blank before 65 being bent to conform to the curvature of the bow;

Figure 3 is a side elevation of the blank illustrating in dotted lines the method of 70 folding the blank to apply the bow;

Figure 4 is a longitudinal sectional view taken through a bow and strip having my fastener applied thereto, and

Figure 5 is a section taken on the line 5—5 75 of Figure 4.

Referring now more particularly to the drawings, the numeral 10 indicates an elongated strip provided upon its sides, and preferably at the ends thereof, with transversely extending flaps or ears 11 which are 80 adapted to be folded upon a line indicated at 12, to occupy a position at right angles to the body portion 10. These ears or flaps 11 are provided therein with openings 13 adapted for the reception of an attaching 85 means whereby the strip 10 may be secured to the bow B of the automobile top. As is well known to those familiar with the art, the bow B is usually provided at the bends thereof with protector strips P formed of 90 metal which surround the bow to prevent breakage of the wood of the bow at the bend. These protector strips have the adjacent ends P' thereof spaced at the outer face of 95 the bow so as to provide a portion where the wood is exposed and in which securing elements may be driven. In the exposed surface of the wood the tangs 15 will engage.

The body portion is cut at points spaced longitudinally thereof on two sides of a 100 triangle, as indicated at 14 and bent upon the third side to form tangs or piercing points 15, which piercing points 15 are adapted to extend through the padding strip 16 and into the bow B. 105

In shipping my device, the strips are pref-

erably left flat, as indicated in Figures 2 and 3, and in application these strips are bent to conform to the curvature of the bow to which they are to be applied, and the ears 5 11 subsequently bent downwardly, as indicated by the dotted lines in Figure 3 to engage the sides of the bow and some suitable attaching means are employed for holding these ears in relation to the bow, as for example a screw or bolt 17. It will of course 10 be understood that the attaching member will be made in various sizes and lengths to accommodate the various sizes of bows and strips employed by the manufacturers of 15 the automobile and carriage tops, it being understood that the strips must be of a greater length than the transverse width of the padding strips.

From the foregoing it will be obvious that 20 I have devised an attaching means for the connecting strips of automobile top bows which is simple in construction and economical to manufacture; and it will likewise be obvious that the construction of the same 25 as hereinbefore set forth is capable of some change without materially departing from the spirit of my invention. I, accordingly, do not limit myself to the specific construction as hereinbefore set forth, except as so 30 limited by the subjoined claims.

What I claim is:

1. In combination with a top supporting bow and a padding strip therefor, an attaching member comprising an elongated 35 body portion provided upon one face with a plurality of integrally attached tangs extending through the strip and engaging in the bow, and means on the ends of said

body portion securing said body portion to the sides of the bow at the sides of the 40 padding strip.

2. In combination with a top supporting bow and a padding strip therefor, an attaching member comprising an elongated body portion provided upon one face with 45 a plurality of tangs extending through the strip and engaging in the upper face of the bow, said body portion extending transversely of the strip and longitudinally of the bow, and means for securing said body portion to the sides of the bow comprising ears formed on the ends of said body portion and engaging the sides of the bow and provided with openings adapted for the reception of a securing medium.

3. In an automobile top, the combination with a substantially U-shaped top supporting bow extending transversely of the top and engaged at the bends thereof by padding strips extending longitudinally of the top, 60 of attaching members for said padding strips each comprising an elongated body portion provided upon one face with a plurality of integrally attached tangs extending through the strip and engaging in the upper 65 surface of the bow at the bends, said strip being curved to correspond to the curvature of the bends of the bow, and ears formed upon the ends of the sides of said body portion and engaging the sides of the bow, said 70 ears having openings formed therein for the reception of a securing medium.

In testimony whereof I hereunto affix my signature.

GUSTAVE H. PRIGAN.
